ELECTRICALLY HEATED BRANDING IRON

Filed Nov. 15, 1930

2 Sheets-Sheet 2

UNITED STATES PATENT OFFICE

HARRY A. PEARCE, OF EL PASO, TEXAS
ELECTRICALLY HEATED BRANDING IRON

Application filed November 15, 1930. Serial No. 495,969.

This invention relates to branding irons used for imprinting indicia on various articles.

5 A primary object of the invention is to provide a branding device which may be used for marking either flat surfaced or curved surfaced articles, the holder for such articles being easily reversible without detaching the holder from the jaw carrying it.

10 Another object is to so construct and mount an article holder to be used in branding with this device so that it may be adjusted to center the type or rather to center the article in relation to the type so that the brand may be placed on the article at the desired point.

10 Another object of the invention is to so construct a brander of this character that the type box and heating unit may be quickly detached and applied to facilitate changing of the type when desired and for varying the connections of the heating cord to control the heat of the heating unit.

In carrying out these objects, the invention is susceptible of a wide range of modification without departing from the spirit or sacrificing any of the advantages of the claimed invention; there being shown in the drawings for illustrative purposes a preferred and practical form, in which:

30 Figure 1 represents a side elevation of a branding tool constructed in accordance with this invention with the jaws shown separated to receive the article to be stamped or branded;

35 Fig. 2 is a bottom plan view thereof with the article holding plate shown in position for holding a pen or pencil or other curved article to be marked;

Fig. 3 is a bottom plan view showing the holding plate arranged to support a flat article;

Fig. 4 is a longitudinal section taken on the line 4—4 of Fig. 2;

Fig. 5 is a similar view taken on the line 45 5-5 of Fig. 4; and

Fig. 6 is a end elevation of the tool.

The branding or marking device constituting this invention comprises an upper handle member 1 and a lower handle member 2 having offset front portions which are arranged

to intersect each other scissors-like and are pivotally connected or fulcrumed at 3. These handle members are made substantially inverted U-shaped in cross section, one being designed to receive and house a coiled spring 4 and the other an electric cord guide sleeve 5 as shown clearly in Fig. 4. In Figs. 1, 2, 3, 4, and 6 this tool is shown in inverted position, the handle 2 being designed to carry the upper jaw member 10 and the handle member 1 carries the lower jaw 20.

The upper jaw member 10 is pivotally connected between two forwardly extending fingers 6 and 7 carried at the front end of the handle 2 which fingers straddle the jaw member 10 and are pivotally connected thereto intermediate the length thereof by a pivot 8. The front portion of this jaw member 10 is cut out at its inner face to form a recess 11 to receive and support the box 12 which carries both the heating unit 15 and the branding element 13, the latter being removably held between two clamping plates 14 and 14a arranged adjacent the heating unit 15 and held in adjusted position by a screw bolt 16 adjustably mounted in the front end of the box 12 and provided with a thumb nut or handle 17 for operating it. At the rear end of the recess 11 is a shoulder 18 and opening through the front wall thereof is a longitudinally extending socket 19 designed to receive a longitudinally extending post 12a carried by the rear wall of the box 12 and which is held in place in the socket by friction, the shoulder 18 being designed to abut against the rear wall of the box 12 when the parts are assembled.

Carried by the rear wall of the box 12 above the jaw 10 is a sleeve 30 which communicates with the interior of the heat unit 90 compartment 12b of the box 12 as shown clearly in Fig. 4 and which is designed to form a cord guide and housing for the electric conductor 31, the negative and positive wires of which divide at the front end of the cord and are provided with clips 32 for connecting them with the poles or contacts 33 of the heat unit. A plurality of these poles 33 are carried by the unit and arranged in longitudinally spaced relation so that the conduct- 100

ing wires may be connected with those closer together or further apart to vary the heating effect, it being understood that the further apart the contacts are the greater the resistance will be and the less heat generated, while the closer together the greater will be the heat. The heating unit of course is made of a current resisting element 34 of any suitable material for this purpose.

- 10 The rear end of the jaw member 10 is reduced and made semi-circular in form to fit in the inverted U-shaped handle member 1. A shoulder 35 is formed in the upper face of this extension as shown clearly in Fig. 4 and 15 designed to abut a pin 35a extending transversely through the handle 1 for limiting the opening movement of the jaws under the action of the spring 4 as will be presently more fully described.
- 20 The lower jaw 20 is arranged between two forwardly extending fingers 6a and 7a carried by the front end of the handle 1 and pivotally connected with said fingers by a combined spring support and pivot bolt 21.
- 25 The rear end of this jaw 20 extends between the side walls of the handle member 2 and is slidably mounted therein and is provided at its terminal with a reduced extension 22 having a shoulder 23 at its rear end designed 30 to abut a pin 24 extending through the handle member 2 and which limits the opening movement of the jaw 20. The coiled spring 4 is connected at one end to the reduced extension 22 of the jaw 20 and at its other end 35 is attached to a lug 25 struck out of the handle member 2 as is shown clearly in Fig. 4. The jaw member 20 has a longitudinally extending slot 26 near its front end through which is designed to be passed a screw threaded 40 post 27 carried by the article holder made in the form of a plate 28, said plate being held clampingly engaged with the jaw 20 by means of a wing nut 27a carried by the post 27 as is shown clearly in Fig. 4. This article 45 holder 28 is designed to be removably and adjustably mounted on jaw 20 by the means just described and has formed at one end thereof a trough-like seat 29 designed to hold a pencil or the like which is to be marked by 50 the branding element 13.

An article clamping spring 36 designed to cooperate with the holding plate 28 is made of comparatively heavy spring wire and bent intermediate its ends to form a loop 37. This 55 loop 37 is bent forwardly and engaged with the jaw 20, being so bent as to straddle the jaw as is shown clearly in Fig. 1. The arms of this spring at the rear end of the loop 37 are coiled around bolt 21 as shown clearly 60 in Figs. 2 and 3 of the drawings, the spring then extends forwardly with the arms 38 diverging for a portion of their length and then extended forwardly parallel with each other and these parallel portions lie in engagement 65 with the lower face of the plate 28 to form

clamping fingers 29 designed to hold securely between them and the plate the article to be stamped or branded.

In Figs. 1, 2, 4, and 6 the article holding plate 28 is positioned so that the seat 29 will be arranged directly over the branding element 13 and thus provides for the stamping or branding of indicia on a rounded article such as a pencil or pen which is held in the seat 29 by the clamping fingers 39.

In Fig. 3 the plate 28 is shown shifted for use in connection with other articles such as flat pieces of leather and the like which it is desired to stamp. This shifting is accomplished by merely loosening the thumb nut 27a and turning the plate into the desired position, the slot in the jaw 20 permitting this adjustment.

It will be obvious that when the parts are connected as shown and described the coiled spring 4 will hold the jaws 10 and 20 open, their opening movement being limited by the engagement of the shoulders on said jaws with the pins 24 and 35a. When it is desired to brand an article the article to be marked is placed between the clamping fingers 39 and the plate 28, the implement being reversed from the position shown in the drawings so that the jaw 20 will be the bottom jaw and the jaw 10 the top jaw and then the current is turned on by a suitable switch, not shown, and flows through the heating element or unit 15, the resistance of which causes the necessary heat for heating the branding element 13. When this element 100 13 has become sufficiently heated the jaws are brought together by pressure exerted on the handles 1 and 2 against the tension of the spring 4 and the mark or indicia carried by the element 13 will be transferred or branded onto the article to be marked.

It is of course understood that the branding element 13 may be changed to meet the requirements of the user by simply taking out the box 12, releasing the plates which clamp said element by unscrewing the screw 16 and placing a desired branding element in its place.

It will thus be seen that this tool is similar in construction to a pair of pliers with the handle members 1 and 2 crossing each other and pivotally connected at their points of intersection. These members are held normally open by the spring 4. The jaws 10 and 20 being pivoted intermediate their ends to the front ends of the handle and extended back into said hollow handle under the pins 24 and 35a are guided and held so that when the handles are closed and opened the jaws will move uniformly toward and away from each other to provide the necessary contact between the branding element 13 and the article to be marked.

When the handles 1 and 2 open to a predetermined extent under the action of the spring 130

4 carrying with them the jaws 10 and 20 the shoulders on the rear portions of these jaws will abut the pins above mentioned and limit the opening movement of the handles and the 5 jaws.

This tool is extremely simple and compact and the heating unit carrying the branding element may be readily removed when desired by simply lifting out the box 12 from 10 engagement with the jaw 20 and disconnecting the conductor cord from the heater element.

Without further description it is thought that the features and advantages of the invention will be readily apparent to those skilled in the art, and it will, of course, be understood that changes in the form, proportion and minor details of construction may be resorted to, without departing from the 20 spirit of the invention or its scope as claimed.

I claim:

1. A branding iron comprising a plier-like structure including pivotally connected normally open handles, jaws carried by said 25 handles and movable toward and away from each other on the closing and opening of the handles, a marking element carried by one of said jaws, and an article holder by the other, said holder having a seat to receive 30 an article to be marked and adapted to be swung laterally to position it in proper relation to the marking element.

2. A branding iron comprising a plier-like structure including pivotally connected normally open handles, jaws carried by said handles and movable toward and away from each other on the closing and opening of the handles, a marking element carried by one of said jaws, and an article holder by the other, 40 said article holder being mounted to swing laterally and having means to support either flat or curved articles for operatively positioning them in relation to the marking element.

45 3. A branding iron comprising a plier-like structure including pivotally connected normally open handles, jaws carried by said handles and movable toward and away from each other on the closing and opening of the handles, a marking element carried by one of said jaws, and an article holder by the other, said holder being in the form of a plate having a trough extending along one edge thereof, and means for mounting said holder 50 on said jaws to provide for its lateral swinging to position the trough in operative relation to the marking element when desired.

60 4. A branding iron comprising a plier-like structure including pivotally connected normally open handles, jaws carried by said handles and movable toward and away from each other on the closing and opening of the handles, a marking element carried by one of said jaws, and an article holder by the 65 other, said marking element being in the

form of a detachably mounted box having a heating unit therein and a branding element arranged in conjunction therewith to be heated thereby.

5. A branding iron comprising a plier-like 70 structure including pivotally connected normally open handles, jaws carried by said handles and movable toward and away from each other on the closing and opening of the handles, a marking element carried by one 75 of said jaws, and an article holder by the other, said marking element including an electrically heated unit with a branding element arranged adjacent thereto to be heated thereby, said box being detachably mounted on 80 its supporting jaw.

6. A branding device comprising a pair of jaws movable toward and away from each other, one of said jaws carrying an article holder and the other having a seat formed 85 therein, a box removably mounted in said seat, a heating unit mounted in said box, a branding element arranged to be heated by said unit and to cooperate with said holder for marking the article to be branded, and 90 means for supplying an electric current to said heating unit.

7. A branding device comprising a pair of jaws movable toward and away from each other, one of said jaws carrying an article 95 holder and the other having a seat formed therein, the other of said jaws having a seat with a shoulder at its inner end and provided with a longitudinally extending socket opening through said shoulder, and a branding 100 element having a longitudinally extending plate for frictional mounting in said socket to hold the element in operative position relative to the article to be branded.

8. A branding iron comprising a plier-like 105 structure including pivotally connected normally open handles, jaws carried by said handles and movable toward and away from each other on the closing and opening of the handle, a marking element carried by one of 110 said jaws, an article holder carried by the other jaw and having a recess, a clamping spring mounted on the holder-carrying jaw and having arms arranged to cooperate with said holder to secure the article to be marked 115 in the recess in the holder.

HARRY A. PEARCE.
